CLAIM

The ornamental design for a lock handle assembly, as shown and described.

DESCRIPTION

FIG. 1 is a perspective view of the lock handle assembly.

FIG. 2 is a front view thereof.

FIG. 3 is a left end view thereof.

FIG. 4 is a right end view thereof; and,

FIG. 5 is a side view thereof, the opposite side being a mirror image thereof.

The unclaimed bottom, being mountable to an ancillary structure, has no design features.
